STABILIZATION CIRCUIT FOR ARC LAMPS
Lester F. Bird, Newark, N.J., assignor to Engelhard
Hanovia, Inc., a corporation of New Jersey
Filed Apr. 28, 1959, Ser. No. 809,485
3 Claims. (Cl. 323—89)

This invention relates to a stabilization circuit for arc lamps and, more particularly, for high pressure arc lamps of the compact type.

It has been found from life tests on high pressure arc lamps of the compact type that unnecessary instantaneous current demands from the electrodes considerably shorten the life of such lamps. Accordingly, circuits which maintain lamp voltages at the lowest value despite variations in line voltage yield the best useful life for the lamp. With the usual ballast for the arc composed of a constant series reactance, there is no compensation for varying supply voltages and the life of the lamp is relatively short. Such arrangements also have the obvious drawback that light from the lamp will flicker with supply voltage variations.

It is further noted that prior circuits which have been effective for accomplishing this purpose have generally been unnecessarily expensive in the provision of heavy duty regulator circuits having an unnecessarily broad range of regulation.

Therefore, it is the principal object of this invention to provide an improved operating circuit for arc lamps, in which the power supplied to the lamp is maintained substantially constant. As a result, the useful life of the lamp is greatly increased. As a further advantage, the light output remains independent of variations in the supply voltage.

In accordance with an illustrative embodiment of the invention, stabilization for arc lamps is obtained by the use of an inductive ballast of which the impedance is regulated automatically as a function of the supply voltage. This is accomplished by means of a pair of saturable reactors, the power winding of each reactor being connected to receive one half-wave of the supply current. In order to vary the impedance of these power windings, two magnetic fields are applied to the magnetic core of each reactor. The first magnetic field has a constant magnetic force above that required for the impedance at which optimum supply current conditions prevail. The magnetic force of the second field is weaker and a function of the supply voltage; it is applied to the core in opposite polarity with respect to the first field. By superposition both fields act combined upon the core to automatically adjust the impedance, and therefore maintain the voltage at the arc lamp at a substantially constant value.

In practice, each reactor core carries two control windings of which the first receives a constant, direct current signal while the second control winding is energized by a direct current signal which is a function of the supply voltage. Since control windings of saturable reactors must necessarily be energized by direct current, two reactors are required, whereby the power winding of each reactor is associated with a rectifier. Each winding receives one of the half-waves of the supply current or a portion thereof as this is the case when an additional, constant impedance is connected in parallel with respect to the power windings.

In accordance with a feature of the invention, the heavy duty inductive ballast of an arc lamp is shunted by a magnetic amplifier having a power capacity which is a fraction of that of the ballast. In addition, control signals which are the resultant of a constant signal combined in opposition with a variable line voltage signal are ap-

2

plied to change the impedance of the shunt magnetic amplifier.

The foregoing arrangements have the advantage of providing regulation for an arc lamp by the addition of an inexpensive light duty magnetic amplifier in parallel with the main ballast of the arc lamp circuit. Furthermore, excellent regulation is provided without changing the desired inductive character of the series ballasting circuit for the arc lamp.

10 In accordance with another feature of the invention the ballast for an arc lamp includes two saturable magnetic cores, and circuitry for applying two magnetic fields to each core. The first field has a constant magnetic force higher than that required for optimum current supply to the lamp. The second, weaker magnetic field varies with the supply voltage and is applied to the cores in opposite polarity with respect to the first field to increase the impedance of the ballast as the line voltage increases.

15 The invention will be further illustrated by reference to the accompanying drawing which is a circuit diagram of one embodiment of the invention.

20 The arc lamp 10, which may be a high pressure arc lamp of the compact type, is supplied from an alternating current source through the leads 12 and 14 and a constant inductive ballast 16. The power windings 18 and 20 of a pair of saturable reactors 22 and 24 are connected in parallel with the ballast 16, and therefore with each other, to form an additional, variable ballast. The rectifiers 26 and 28, each associated with one of the power windings 18 and 20, respectively, eliminate one half-wave from the corresponding winding.

25 In order to vary the impedance in the windings 18 and 20 for increasing or decreasing the total ballast in the supply circuit, the reactor 22 is provided with two control windings 30 and 32. In a similar manner, control windings 34 and 36 form part of the saturable reactor 24. Reference numerals 38 and 40 designate the magnetic cores of the reactors which, as a unit, may be considered as a dual magnetic amplifier.

30 Variation of the impedance in the power windings as a function of the supply voltage is obtained by means of direct current signals through the control windings, whereby each half-wave of the total supply current is separately subjected to this correction. Since the impedance in the

35 power windings 18 and 20 is an inverse function of the degree of magnetic saturation in the cores 38 and 40, a decrease in saturation and therefore an increase in impedance must be obtained from an increase in supply voltage. This is accomplished, in accordance with the

40 invention, by applying a constant magnetic field to the cores 38 and 40, the force of this field exceeding that required for optimum current supply to the lamp 10. For this purpose, the control windings 30 and 34 are energized by a sufficiently strong, constant direct current signal which may be obtained from any suitable current source.

45 In practice, the required current is preferably derived from the supply lines 12 and 14 over taps 42 and 44, a voltage stabilizer 46, which may comprise a saturable reactor 48 and a loading capacitor 50, and a full-wave bridge-type rectifier 52.

50 The second, weaker direct current signal, which must be a function of the supply voltage, is obtained by means of taps 54 and 56, through a transformer 58 and a second full-wave bridge-type rectifier 60. The output therefrom is applied to the second control windings 32 and 36. It will be noted that the connections must be made in such a manner that the magnetic field generated by the control winding 32 is in opposite polarity to that generated by the control winding 30. Similarly, the requirement for opposite polarity of the fields set up by the windings 34 and 36 must be fulfilled.

55 In the drawing, in order to illustrate the condition of opposed polarity, the coils have

been shown as being wound in the opposite sense. Obviously, the same effect can be obtained, e.g., by reversing the polarity of one of the rectifiers.

From the foregoing it will be understood that the cores 38 and 40 are subjected to the action of a differential magnetic field which is the result of the comparatively greater magnetic force generated by the constant current signal flowing through windings 30 and 34, diminished by the opposed magnetic force at any particular instant and obtained from the second pair of control windings 32 and 36. In practice, and in order to obtain a large operating range, it has been found advantageous to provide a current in the windings 30 and 34 about twice as strong as the average or optimum current in the windings 32 and 36. In operation, a decrease in line voltage and therefore in the signal current through control windings 32 and 36 results in an increase of magnetization in the cores. The impedance then decreases to permit more current to flow through the power windings 18 and 20 and through the lamp. With increased line voltage, conditions are reversed, that is, with an increase in line voltage, magnetization in the cores decreases to increase the impedance in the power windings. Less current in the supply circuit flows through the lamp and the desired result of power stabilization is obtained. In this regard it will be noted that the magnetic fields set up by the constant current signal in the windings 30 and 34 prevail over the varying supply signal fields generated by the coils 32 and 36; that is true at any particular instant. In each case, the resulting differential magnetic field therefore has the polarity of the first mentioned field and varies as an inverse function of the supply signal through the windings 32 and 36.

In one particular example, the supply voltage had a nominal value of 115 volts and actually varied from about 100 volts to 130 volts. The resulting variable control voltage at the secondary of the transformer 58 varied from $V_{\min}$, when the line voltage was 100 volts to $V_{\max}$, when the line voltage was 130 volts. The constant biasing voltage at the output of the circuit 46 was equal to $V_{\max}$, the maximum value of the variable control voltage. Now, with the constant biasing and variable control signals being applied in opposition to the magnetic amplifier, they cancel out when the line voltage is at the maximum value of 130 volts. Under these conditions the impedance of the magnetic amplifier is high and essentially no current flows through it. When the line voltage drops to 100 volts, however, the differential bias saturates the magnetic amplifier and its impedance drops sufficiently to maintain the arc lamp voltage at a substantially constant level. The minimum impedance of the magnetic amplifier is therefore several times that of the ballast 4, and the power handling capacity of the magnetic amplifier is only a minor factor of that of the ballast.

The subject matter of this application is related to that disclosed in co-pending application Serial No. 781,222, filed December 18, 1958, now abandoned.

It will be obvious to those skilled in the art that many modifications may be made within the scope of the present invention without departing from the spirit thereof, and the invention includes all such modifications.

What is claimed is:

1. An automatically regulated ballast circuit comprising alternating current input means connectable to a current supply, a ballast connected in series in the input means, a pair of saturable reactors having power windings, the ballast including the power windings, means for directing one half-wave of the supply current through the power

windings of one reactor, means for directing the other half-wave of the supply current through the power windings of the other reactor; each reactor having a core and first and second control windings; means for supplying a first, stabilized direct current signal to the first control winding of each reactor for magnetically biasing both cores equally and beyond the saturation degree required for optimum current supply conditions; means for deriving, from the alternating current supply, a second direct current signal which is a function of the supply voltage; and means for supplying said second signal to the second control winding of each reactor for opposing, equally in each core, the saturation produced by the first stabilized direct current signal in the first control winding with the second signal.

2. An automatically regulated ballast circuit comprising alternating current input means connectable to a current supply, a ballast connected in series in the input means, a pair of saturable reactors having power windings, the ballast including the power windings, means for directing one half-wave of the supply current through the power windings of one reactor; means for directing the other half-wave of the supply current through the power windings of the other reactor; each reactor having a core and first and second control windings; means for supplying a first, constant direct current signal to the first control windings of both reactors for magnetically biasing equally both cores; means for deriving, from the alternating current supply, a second direct current signal which is a function of the supply voltage, said second signal current amounting to a value of about half the first signal current in the first control windings; and means for supplying said second signal to the second control winding of each reactor for opposing, equally in both cores, the saturation produced by the first stabilized direct current signal in the first control windings.

3. An automatically regulated ballast circuit comprising alternating current input means connectable to a current supply, a ballast connected in series in the input means, the ballast comprising an inductance having comparatively low impedance and the power windings of a dual magnetic amplifier of comparatively high impedance, each winding being connected in parallel with said inductance; a pair of rectifiers oppositely poled relative to each other and each associated with one of the said pair of power windings, the dual magnetic amplifier having two cores, a pair of control windings being associated with each core; circuitry including a stabilizer and a first bridge-type full-wave rectifier for deriving a first, constant direct current signal from said power supply means; means for applying said first signal to one of the control windings of each core to decrease the impedance in the power windings below the impedance level for optimum current supply conditions; circuitry including a transformer and a second full-wave bridge-type rectifier for deriving, from the alternating current supply, a second direct current signal which is a function of the supply voltage; and means for applying said second signal to the other control windings of each core to increase the impedance in the power windings.
